UNITED STATES PATENT OFFICE.

CHARLES W. SPONSEL, OF WETHERSFIELD, CONNECTICUT, ASSIGNOR TO DOMESTIC STOKER COMPANY, OF NEW YORK, N. Y., A CORPORATION OF DELAWARE.

BURNER PLATE.

Application filed July 7, 1924. Serial No. 724,585.

To all whom it may concern:

Be it known that I, CHARLES W. SPONSEL, a citizen of the United States, and a resident of Wethersfield, county of Hartford, State of Connecticut, have invented certain new and useful Improvements in a Burner Plate, of which the following is a specification.

This invention relates to burner plates for use in burning coal and the like.

10 As an instance of a use to which my improved burner plate may be applied, reference may be had to a furnace of that type wherein the coal or other fuel is fed across the plate, and the air, which supports combustion, is supplied, at least in part, through the plate. It is, of course, understood that the present disclosure is by way of illustration only and is not to be taken as restrictive of my conception, my improved 15 burner plate being susceptible of various modifications and embodiments and being adapted for use in furnaces other than the specific type here shown.

The aim of the present invention is to 20 provide a burner plate of the character described having various features of novelty and advantage and which is particularly characterized in that lodgment of ashes and fuel in the openings through the plate 25 is substantially entirely prevented so that these openings do not become clogged up, which means that the burner plate will be effective and efficient in operation.

A further aim of the invention is to 30 provide a burner plate of simple construction and which may be economically manufactured.

Other objects will be in part obvious and 35 in part pointed out more in detail herein-after.

The invention accordingly consists in the features of construction, combination of elements and arrangement of parts which will be exemplified in the construction hereinafter set forth, and the scope of the application of which will be indicated in the appended claims.

In the accompanying drawing, wherein 40 I have shown, for illustrative purposes, one embodiment which the invention may take:

Figure 1 is a diagrammatic view showing a portion of a furnace in which my burner plate is incorporated;

Fig. 2 is a side view of the burner plate, 45 one-half thereof being shown in central

section and the other half in elevation, with a portion of the skirt broken away;

Fig. 3 is a partial view looking directly down on the fuel supporting surface of the burner plate; and

Fig. 4 is a sectional view taken substantially on line 4—4 of Fig. 3.

Referring to the drawing, and particularly to Fig. 1, *a* designates a portion of the wall of the fire box chamber; *b*, a hopper into which coal or similar fuel is fed; and *c*, a screw for feeding the coal from the hopper up through the gooseneck *d* and onto the supporting surface of the burner *e*. This showing is by way of illustration only. It will be understood that the fuel will be forced outwardly and upwardly of the conical fuel supporting surface of the burner plate while air is fed through suitable openings in the plate so as to support combustion of the fuel. Heretofore, one objection to burner plates of this sort has been that the slots or openings therein soon become clogged up with ashes and fuel, resulting in loss of efficiency. It has been proposed to provide 50 burner plates of this sort with relatively small holes as distinguished from slots, but one objection to such plates has been that they are expensive to manufacture and they are not free from the disadvantage 55 that the holes become clogged up.

In accordance with the present invention, I provide the burner plate with holes so formed and arranged that there is little or no likelihood of them becoming clogged up 60 and, therefore, there is no loss of efficiency in the furnace on this account, and the plate may be very economically manufactured. To these ends, I form, on opposite faces of 65 the plate, grooves which intersect at their bottoms. In the illustrative showing of the drawings, the grooves on the upper or fuel supporting face of the burner are indicated by the numeral 10, and the grooves on the under face, by the numeral 11. It is, of course, obvious that the grooves may be disposed at any desired angle relative to one another and that, instead of the burner plate having a conical fuel supporting surface, it may be flat, and in which instance the 70 grooves on the bottom surface may be at right angles to those on the upper surface, or the two sets of grooves may be inclined to one another. In the drawing, the grooves 10 extend in the direction in which the fuel is 75

fed across the plate, that is to say, they are radially disposed, while the grooves 11, on the under face, are circumferentially disposed. It will be seen, particularly from 5 Figs. 2 and 4, that the grooves 10 and 11 cut slightly into or intersect one another so as to form the openings 12. In the present instance, the depth of the grooves 10 and 11 is very slightly greater than one-half the thickness of the burner plate. The openings 12 10 may be of any suitable shape, as, for instance, square, round or diamond shaped. The desired configuration of opening may be obtained by making the grooves 10 and 11 15 to the proper cross sectional shape and size. It will be seen that the edge of the openings 12 are relatively sharp, this being of advantage in that they provide but little opportunity for the lodgment of fuel or ashes 20 therein and, in the event that ashes or fuel should tend to collect in any of the openings, the same would be easily pried and cut loose.

From the foregoing description, it will be seen that my improved burner plate may be 25 very economically manufactured; for example, the grooves 10 may be very simply and cheaply formed by a milling or planing operation, and the grooves 11 may be formed by a turning operation. Since the openings 30 12 are of relatively small depth, there is

little likelihood of the same becoming clogged up. The ribs 13 between the grooves 10 support the fuel and, to a certain extent, hold the same away from the openings 12. 35 In the event that ashes or fuel should become stuck in any of the openings 12, the fuel, which is moved over the surface of the plate, will strike the stuck particles and pry or fulcrum them loose. It will be seen that 40 the walls of the grooves are inclined towards each other in the direction of the depth of the grooves so that the grooves become of gradually less width, this arrangement being of advantage in that it makes the 45 edges of the openings somewhat sharper than would be the case if the sides of the grooves were parallel.

I claim as my invention:

1. A burner plate comprising an annular body having radially extending grooves in 50 its fuel supporting face and having circumferential grooves in its other face of sufficient depth to intersect the radial grooves.
2. A burner plate having a conical portion provided on its fuel supporting face 55 with radially extending grooves and on its other face with circumferential grooves cutting into said radial grooves.

CHARLES W. SPONSEL.
